CLAIM

The ornamental design for a hood, as shown and described.

DESCRIPTION

FIG. 1 is a front view of a hood showing our new design; FIG. 2 is a right side view thereof; FIG. 3 is a left side view thereof; and, FIG. 4 is a top view of the hood but shown in a different broken line environment.

The broken lines, and the areas within the broken lines illustrate portions of the hood and form no part of the claimed design.
